UNITED STATES PATENT OFFICE

ROLLYN H. BAKER, OF DAYTON, OHIO.

METALLIC BOX.

1,074,539.

Specification of Letters Patent. Patented Sept. 30, 1913.

Application filed May 22, 1911. Serial No. 628,831.

To all whom it may concern:

Be it known that I, ROLLYN H. BAKER, a citizen of the United States, residing at Dayton, in the county of Montgomery and State of Ohio, have invented certain new and useful Improvements in Metallic Boxes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to certain new and useful improvements in metallic boxes such as are used to contain shoe paste, ointment and the like, where a tight-fitting lid is required in order to exclude air. Such boxes are usually made with a circumferential bead lying below and adjacent to the mouth of the box, and the cover is provided with a laterally extended circumferential flange which engages said bead when pushed into position and projects slightly therebeyond.

The object of the invention is to provide means attached to the box which serves a two-fold purpose of a lid raiser and a handle by which the box may be hung up when not in use, or held in the hand while using without soiling the hands.

The accompanying drawings clearly illustrate my invention.

Of these Figure 1 is a side elevation of a box such as referred to above. The lid of the box is shown completely closed, and the attachment in a position for prying up the lid or hanging the box up. Fig. 2 is a similar view showing the lid raised by pressing on the handle. Fig. 3 is a top plan view of a box.

The box 1 is a standard form of box, having the bead 2 extending around it near the mouth, and a lid 3 almost of equal depth having a radially and circumferentially extending flange 4. When the lid of such a box is pressed down so that the flange 4 engages the bead 2, it is hard to open. To facilitate the raising of the lid

and perform other additional useful purposes, I provide a metal bow 5 which may be constructed of a suitable gage of wire or it may be stamped from sheet metal. A portion of the length of this bow follows substantially the contour of the box, and midway in the body thereof a bend is made to form a convenient handle 6. The extreme ends of said bow terminate in rounded or cam portions 7 which lie inwardly and snugly against the sides of the box and below the flange 4 of the cover. These ends are neatly pivoted at 8 to the sides of the box just below the bead 2, and the formation of the extreme ends is such as to permit them to clear said bead when prying up the lid.

It will be at once seen that in terminating the lifter in the form of a useful handle and hanger, considerable leverage is provided, which requires only a slight effort to raise the lid. When using the contents of the box, the handle portion 6 affords means for holding the box so that the hand will not be soiled, and as before stated, the handle may be utilized for suspending the box when not in use. In holding the box by means of the handle 6, the fingers of the hand naturally engage the bottom side of the box while the thumb engages the upper side of the said handle portion; the box is thus held in a horizontal position by one hand while the other hand applies the contents. The hand which holds the box in such manner is prevented from coming in contact with any of the contents of the box.

Having described my invention and set forth the essential characteristics thereof, I claim:

A metallic box having a lid with a laterally extended marginal flange therearound, a handle for said box consisting of a flat band a portion of which is shaped to conform to the contour of the box and the ends of which are pivoted to opposite sides of the box, at the center of the circumference of said box, the said ends being tapered and extended to conform to the circumference of the box beyond the pivots and ex-

tended upwardly to engage the flange of the cover, the portion of said handle lying beyond the circumference of the box being formed into a loop which serves as a hand grip in using said box and as a hanger for the box when it is not in use, as shown and described.

In testimony whereof I affix my signature, in presence of two witnesses.

ROLLYN H. BAKER.
